CAR ICING SYSTEM

Charles K. Faye, San Francisco, and Ira C. Baldwin, Portola, Calif., assignors to The Western Pacific Railroad Company, San Francisco, Calif., a corporation of California

Application December 14, 1948, Serial No. 65,172

8 Claims. (Cl. 62—1)

1

Our invention relates to the icing of refrigerator cars; and the broad object of our invention is the provision of means by which ice suitably cracked, together with salt, may be deposited in the roof hatches of refrigerator cars. Other objects include the provision of such means which is reasonable in first cost, maintenance and operation, and by which the operation of icing a train may be cut to the minimum of time.

Still another object of the invention is the provision of an improved means for breaking up large cakes of ice into smaller pieces.

Our invention possesses other objects and features of value, some of which, with the foregoing, will be set forth in the following description of our invention. It is to be understood that we do not limit ourselves to the showing made by the said description, and the drawings, as we may adopt variant forms of our invention within the scope of the appended claims.

In the drawings, Figure 1 is a vertical sectional view of a principal portion of our apparatus, including the breaker rotor, part of the conveyor system, and driving motor. The plane of section is indicated by the line 1—1 of Figure 3. Figure 2 is a plan view of the motor and driving connections. Figure 3 is a vertical sectional view taken in the plane indicated by the line 3—3 of Figure 1. Figures 4 and 5 are respectively side and end elevations of the breaker rotor. Figure 6 is a vertical sectional view through the structure taken in the plane indicated by the line 6—6 of Figure 9. Figure 7 is a bottom view of the chute end. Figure 8 is a cross sectional view taken in the plane indicated by the line 8—8 of Figure 6. Figure 9 is a plan view, partly in diagram, showing the apparatus with reference to two refrigerator cars in position for the icing of one end of each. Figure 10 is a cross sectional view of the delivery chute, taken in the plane indicated by the line 10—10 of Figure 6. Figure 11 is a plan view of the icing system in accordance with the invention showing the layout of the stationary ice trough fitted with an endless conveyor adjacent to a plurality of refrigerator cars on the railway tracks therealong, adapted to be selectively supplied with the crushed ice moving along the trough.

A heavy percentage of freight moved by rail is carried in refrigerator cars which are cooled by ice. With the increase in volume of such shipments, and the rising cost of all labor, the problem of icing the cars has become a serious one. While our invention does not wholly dispense with human effort, manual labor in handling

the apparatus is reduced to a minimum; and a small operating crew can service an entire train of refrigerator cars in a fraction of the time formerly required by a much larger crew working under older methods. The saving of time in the icing of the cars by our system is one of its chief advantages; and this saving is reflected in many betterments—speeding up of shipments, lessening of spoilage, preservation of quality of cargo, lessened labor costs and others.

In terms of broad inclusion, the system of our invention comprises a supporting framework arranged along a railroad track where a train of refrigerator cars may stop. An ice breaker rotor is located in the upper part of the frame for breaking up large cakes of ice which are carried to the rotor from a conveniently located storage by a suitable conveyor.

The cracked ice falls into a long trough supported on the framework and extending along the track but high enough to be well above the roofs of the cars awaiting icing. One reach of an endless chain is arranged in the trough with drag blades to move the broken ice along with the chain.

At suitable intervals corresponding to the length of the cars, loading stations are provided. At these points the bottom of the conveyor trough is provided with gate means for dropping the ice into a distributor chute down which the ice flows to a selected ice hatch in the car roof. The distributor chute is adjustable both as to length and angular position, and when the adjacent ends of two cars are spotted opposite the loading station, each of the four hatches in the adjacent ends of the cars is readily reached by the chute. The same condition exists at the next loading station, at which the ends of two adjacent cars lie within easy range of the distributor chute at that station.

As many loading stations as desired are disposed along the track at such intervals as permit the spotting of a succession of cars; and each station is supplied with cracked ice from the conveyor trough. When the gate at a given station is closed, the cracked ice in the conveyor trough passes through that station and on to the next station where it may or may not be dropped into a distributor chute according to the setting of the gate means at that point.

It will therefore be understood that with three loading stations for example, the spotting of the forward end of the first car opposite the first station will simultaneously spot the rear end of the first car and the forward end of the second car.

opposite the second station, and the rear end of the second car and the forward end of the third car opposite the third station. This places each of the first ten loading hatches within range of a distributor chute. After the necessary ice has been dropped through these hatches, the train is advanced to spot the succeeding series of cars, until all have been iced.

A detailed description of our system follows.

Along a straight stretch of railroad track where a train of refrigerator cars may pause, a long framework comprising vertical members 2 and horizontal members 3 is erected. Supported in this framework and lying substantially parallel to the vertical plane of the near rail is a trough having a bottom 4 and vertical sides 5. The trough carries the upper reach of an endless conveyor chain, including the two side chains 7 and the drag blades 8 secured to the chains and extending across the trough.

The chain is of course carried by sprockets at each end, only the driving sprocket 9 at the right of Figure 1 being shown; since the construction and mounting of the sprocket at the opposite end is obvious. A pair of guides 12 is also preferably provided below the main trough to support and guide the lower reach of the chain; and to ease the entry of the drag blades into the upper trough, the sides are flared outwardly and the bottom angled downwardly at the end near the driving sprockets.

The driving sprocket 9 is fixed on a shaft 13, journaled in bearings 14, secured to frame members; and the shaft is rotated by gears 16, connecting it to shaft 17, journaled in bearings 18 and connected through a gear train in housing 19 with the electric motor 21. Rotation of the motor 21 is therefore effective to drive the conveyor chains in the direction indicated by the arrows, moving the drag blades through the trough.

Means including mechanism for breaking up large cakes of ice are provided for supplying a substantially continuous flow of cracked ice into the end of the trough near the incoming drag blades. Journaled in bearings 22, supported on its frame, is a shaft 23, having radial flanges 24 at the ends, and flanges 25 dividing the shaft into three portions as best shown in Figure 4. Extending between the flanges and welded thereto are four evenly spaced head bars 27 of square cross section, and with the two inner sides lying in planes tangent to the shaft.

Mounted in each head bar and extending out tangentially from the outer leading face thereof are three breaker points, the outer points 28 being longer than the middle points 29. These points are of square cross section in their main body portion, which seats in a shallow transverse groove in the head to prevent twisting of the point. The shank 31 of the point is tapered to fit a tapered hole in the head bar; and a nut 32, threaded on the shank, holds the point securely in its seat. The outer end of the point is tapered and slightly hooked forwardly as shown; and because of the tangential mounting of the points, they tend to draw the ice into the breaker rotor, rather than push it away.

The breaker rotor shaft 23 carries on one end the sprocket 35, connected by chain 36 to the sprocket 37, fixed on shaft 38, which is driven by a worm gear in housing 39 from the shaft 41, coupled to the shaft 42 of the motor 43. Engaging the outer side of one reach of the chain 36 is a sprocket 44, fixed with a smaller sprocket 46 75

on a shaft 47, journaled on the link 48, which at the other end, is pivoted on the shaft 49, journaled in bearings 51, mounted on vertical frame members.

Fixed on the shaft 49 is a sprocket 52, connected by chain 53 to the sprocket 46, so that the shaft 49 is rotated in time with the breaker rotor. This is important since the shaft is utilized to operate conveyor means to bring cakes of ice to the breaker rotor. Extending from just below the breaker rotor to a convenient loading point is an elevator trough or chute 54, in the middle of which is the endless chain 56 with spikes 57 at intervals extending into the trough bottom 58 far enough to engage ice cakes placed therein and propel them along to the breaker rotor. The chain runs over sprockets, one of which 59 is fixed on the shaft 49. In Figure 1 of the drawings only the ends of the elevator chute and chain nearest the breaker rotor is shown, the opposite or lower end terminating in a convenient place for loading the elevator from an ice storage room or from a truck.

The bottom of the elevator chute is extended beyond the sprocket 59 in a portion 61, ending directly below the rotor shaft 23; and a steel plate 62 connects the high edge which is just missed by the swinging points 28, with the bottom 63 of the trough 64, which discharges into the trough 66, having the sloping bottom 67, which in turn discharges into the main conveyor trough 4-5.

In order to insure that no large chunks of ice pass the breaker rotor, triangular blades 68 are bolted to the trough bottom 63; and extend through the steel plate 62, within but to one side of the sweep of the points 28 and 29. To insure the delivery of the ice cakes to the downsweeping breaker points, a weighted hold-down rack 69 is pivoted on the frame with its free end arranged to bear on the ice cakes just in front of the breaker rotor. On the opposite side of the rotor, a guard plate 71, fixed to the frame, prevents ice chunks from being thrown out of the trough.

From the above it will be clear that cakes of ice from storage are loaded into the elevator trough 54, and carried by the chain 56 into the sweeping breaker points 28 and 29 which, with the fixed blades 68, reduce the cakes to the desired size chunks, forcing them through the short trough 64 into the sloping trough 66, from which they slide into the main conveyor trough to be caught and carried therealong by the drag blades 8.

The frame may be provided with a single loading station and distributor chute to be supplied to the conveyor trough, or it may be extended to include a number of loading stations, each with its distributor chute, and spaced apart a distance corresponding to the length of the cars, so that a series of cars may be properly spotted, and all iced without again moving them. For purposes of this explanation an extension of the frame and conveyor trough (to the left of Figure 1) to include three loading stations is assumed. Figure 9 illustrates in plan, the apparatus so far explained and including the first loading station. Three loading stations are shown fully in Figure 11, with the first station in operating condition.

Below the level of the upper reach of the conveyor chain 1 and pivotally mounted on the bracket 76 for movement in vertical and horizontal planes is a chute 77. The chute is connected by pivot pin 78 through its bottom wall with the cross bar 79, journaled at its ends in the bracket. Along the upper edge of each side of

the chute and extending well beyond its free end, a split tube 81 is secured; and a bridle 82 pivoted to the tube ends is connected to a cable 83 running over fixed pulleys 84 in the frame to a counter weight 85.

In order to give greater range to the chute, it is provided with an extension 87, lying on the outside of the chute and suspended therefrom by hangers 88 extending through the slots of the tubes to small carriages 89 on the inside. A hand-hold 91 on each side of the extension near its free end provides convenient means for manually controlling both the position of the chute and the degree of its extension. The importance of such control is illustrated in Figure 9, where two adjacent cars 92 and 93 are shown spotted opposite the first loading station, so that each of the four ice hatches 94 in the ends of the cars are readily reached without moving the cars.

Means are provided for dropping ice from the main conveyor trough into any selected distributor chute in the system. At each loading station and immediately above the flared end of the distributing chute, is a gate 96, framed between angle iron sides 97, which are pivoted at 98 on one side of the conveyor trough and movable from its upper position, in which it forms part of the floor of the trough (over which ice may be dragged to the next loading station) to its lower position, in which it forms with the fixed sides 99 a connecting trough between the main conveyor trough and the distributing chute. A fixed rail 100 across the gate opening on each side gives support to the conveyor chain and blades when the gate is open; and a removable pin 102 in a vertical member of the frame under one of the angle iron sides of the gate holds it in upper or raised position.

Side walls 103 are fixed to the gate at its free end to prevent loss of ice between it and the chute; and this walled section is also useful in preventing loss of salt as it pours from the spout 104, located directly above the free end of the gate. Since a certain quantity of salt is added to each charge of ice loaded into the car hatch, a salt bin 106 is arranged at each loading station above the gate. The bin has a sloping bottom 107 so disposed as to empty into the spout. Slides 108 and 109 at opposite ends of the spout are pivotally connected to the lever 110 which is pivoted on the bracket arm 112. As one slide opens, the other closes. In the position of the parts shown in Figure 6, the spout has filled with salt, the size of the spout having been calculated to hold a desired unit volume. At the proper time, one of the operating crew raises the slide 109, simultaneously closing the slide 108, thus releasing a charge of salt, which falls into the walled end of the gate to be swept down the chute and into the ice hatch by the stream of ice.

When the loading of the necessary charge of ice and salt into each of the loading hatches of the cars 92 and 93 has been completed, the gate is raised and the pin 102 inserted, whereupon the drag blades convey the ice straight through the station and on to the next open gate, where ice and salt are dropped into the distributor chute at that station, and loaded into the waiting hatches. The first chute extension is now pushed back onto the chute, and the whole chute structure raised out of the way where it is held by the counterweight, since the center of gravity of the chute structure is nearer its pivotal mounting in telescoped position and therefore the weight operates on a shorter lever arm.

When the series of cars first spotted at the loading stations have been iced, the motors 21 and 43 are stopped, and the train is moved along the track to spot a succeeding series of cars at the loading stations, whereupon the same cycle of operations is repeated.

We claim:

1. A car icing system comprising a stationary frame to one side of the right-of-way on which the cars may move, an ice crushing mechanism on said frame, a trough for receiving the crushed ice from said mechanism extending along the side of and in parallel to said right-of-way, means for moving the crushed ice along said trough, a distributor chute having its inlet end adjacent to said trough and its outlet end in direct discharging relation to the loading hatches of refrigerating cars on said right-of-way, and means comprising a part of the trough bottom for selectively diverting the crushed ice moving along said trough to the inlet end of said distributor chute.

2. A car icing system comprising a stationary frame to one side of the right-of-way on which the cars may move, an ice crushing mechanism on said frame, a trough for receiving the crushed ice from said mechanism extending along the side of said right-of-way, an endless conveyor movable in said trough for advancing the crushed ice therealong, a movable distributor chute having its inlet end mounted below said trough and its outlet end in discharging relation to the loading hatches of a plurality of refrigerating cars on said right-of-way, and means forming a part of the trough bottom for selectively diverting the crushed ice moving along said trough into the inlet end of said distributor chute.

3. An apparatus as set forth in claim 2 wherein the last-mentioned means comprises a cover for an opening in the trough bottom which is tilted to act as an auxiliary chute from the trough bottom to the inlet of the distributor chute.

4. A car icing system comprising a stationary frame having a plurality of icing stations, said frame disposed on a side of the right-of-way on which a plurality of cars may be positioned for icing, said icing stations being longitudinally spaced along said frame in correspondence to the length of the cars being iced and the corresponding displacement between the sets of ice loading hatches in said cars, an ice crushing mechanism at one end of said frame, a platform for receiving the crushed ice from said mechanism extending along the side of said right-of-way, conveyor means for moving the crushed ice along said platform from said end, a distributor chute at each one of said icing stations having its inlet end mounted below said platform and its outlet end in discharging relation to the loading hatches of refrigerating cars on said right-of-way, and means at longitudinally displaced points of said platform and corresponding to the displacement between said icing stations for diverting the crushed ice moving along said platform into the respective inlet ends of said distributor chutes at said icing stations.

5. A car icing system comprising a stationary frame having a plurality of icing stations, said frame disposed on a side of the right-of-way on which a plurality of cars may be positioned for icing, said icing stations being longitudinally spaced along said frame in correspondence to the length of the cars being iced and the corresponding displacement between the sets of ice

loading hatches in said cars, an ice crushing mechanism at one end of said frame, a trough for receiving the crushed ice from said mechanism extending along the side of said right-of-way, a conveyor for moving the crushed ice along said platform from said end, a movable distributor chute at each one of said icing stations having its inlet end mounted below said trough and its outlet end in discharging relation to the loading hatches of refrigerating cars on said right-of-way, and a movable gate bottom at longitudinally displaced points of said trough and corresponding to the displacement between said icing stations for selectively diverting the crushed ice moving along said trough into the respective inlet ends of said distributor chutes at said icing stations.

6. An apparatus as set forth in claim 5 wherein each chute is rockable at its inlet end and is extensible so that the ice discharged thereinto by said movable gate bottom may be discharged selectively into the hatches of a plurality of cars positioned on a plurality of tracks of said right-of-way with said hatches in proximity to the respective icing station.

7. A car icing system comprising a stationary frame having a plurality of icing stations, said frame disposed on a side of the right-of-way on which a plurality of cars may be positioned for icing, said icing stations being longitudinally spaced along said frame in correspondence to the length of the cars being iced and the corresponding displacement between the sets of ice loading hatches in said cars, an ice crushing mechanism at one end of said frame, a trough for receiving the crushed ice from said mechanism extending along the side of said right-of-way, an endless conveyor for advancing the crushed ice along said trough from said end, a movable distributor chute

5
10
15

at each one of said icing stations having its inlet end oscillatably mounted about a vertical axis below said trough at one side thereof and its outlet end in discharging relation to the unloading hatches of refrigerating cars on said right-of-way, and a pivoted gate bottom at longitudinally displaced points of said trough and corresponding to the displacement between said icing stations pivotally mounted on the opposite side of said trough around an axis parallel to the longitudinal axis thereof for diverting the crushed ice moving along said platform into the respective inlet ends of said distributor chutes at said icing stations.

8. An apparatus as set forth in claim 7 wherein a salt bin is provided in said frame above the inlet end of each distributor chute and said salt bin having a control gate for transferring salt from said bin to said chute therebelow.
